Patented Mar. 11, 1924.

UNITED STATES PATENT OFFICE.

WILLIAM A. GIBSON, OF DETROIT, MICHIGAN.

PNEUMATIC JACK.

Application filed March 13, 1922. Serial No. 543,230.

To all whom it may concern:

Be it known that I, WILLIAM A. GIBSON, a citizen of the United States of America, residing at Detroit, in the county of Wayne 5 and State of Michigan, have invented certain new and useful Improvements in Pneumatic Jacks, of which the following is a specification, reference being had therein to the accompanying drawings.

10 This invention relates to devices known as lifting jacks, and more particularly to devices especially adapted for use in connection with motor vehicles. It is an object of the invention to provide a device of very 15 simple construction wherein the device is operated by compressed air.

A further object is to provide an air container into which air may be forced under pressure to operate the device in raising a 20 load and which container is of simple construction and efficient in operation, all liability to leakage being obviated.

A further object is to provide certain other new and useful features in the construction 25 and arrangement of parts, all as hereinafter more fully described.

With the above and other ends in view, the invention consists in providing an expandable metal casing, and inclosing within this 30 casing an inflatable air container adapted to expand under pressure to expand the casing and operate the device in raising a load.

The invention also consists in certain new 35 and useful features in the construction and arrangement of parts and in the matters hereinafter set forth and more particularly pointed out in the appended claims, reference being had to the accompanying drawings, in which—

40 Fig. 1 is a vertical section through a device illustrative of the invention, with the base or foot portion thereof shown partly in elevation, and

Fig. 2 a plan view of a stand or base 45 of the device detached.

The device as shown in the accompanying drawing comprises a metal stand 1 having a flanged base 2 adapted to form a firm support for the device so that it will stand 50 upright. Rising from the base is a hollow pedestal 3 having a head 4 at its upper end which head is cup-shaped or provided with a hemispherical cavity 5 in its upper end, the side wall of the head being cylindrical 55 and meeting the surface of the cavity in a substantially sharp annular rim or ridge 6.

Sleeved over the head 4 is a tubular member or sleeve 7 with the upper end of the sleeve closed air tight and of semi-spherical form so that the inner face of the end wall 8 of 60 the sleeve will form substantially a continuation of the face 5 of the cup. This sleeve is of a diameter to fit closely over the head 4 and slide freely thereon, and secured in any suitable manner to the upper end of the 65 sleeve is a stem 9 which may be formed tubular, as shown, with the wall of the tube flanged outwardly at its lower end and riveted or otherwise secured to the end wall 8 of the sleeve. Carried by the upper end of 70 the stem 9 is a suitable cast metal head 10 formed with a tubular portion 11 to fit over the upper end of the stem 9 and is secured in place thereon by forming an annular groove 12 in the stem and in turning the 75 lower edge of the sleeve portion 11 into this groove.

Seated within the seat or cup 5 of the head 4 is an expandable and inflatable air bulb 13 formed preferably of rubber and provided 80 with a stem 14 extending downward through an opening 15 in the bottom portion of the cup. This stem is adapted to contain the usual valve mechanism (not shown) for permitting a free flow of air into the bulb 85 and checking the discharge therefrom. The lower end of the stem 14 may be provided with a suitable connection 16 by means of which an air hose may be attached to the stem and air under pressure forced there- 90 through into the bulb 13.

The semi-spherical upper end 8 of the sleeve 7 forms a smooth interior seat for the bulb 13 and the cup 5 forms a like seat for the bulb upon the stationary pedestal or 95 stand 1, and as the rim 6 of the cup is comparatively sharp, no shoulder is formed where it meets the inner surface of the sleeve 7 which would be liable to injure the bulb when the same is inflated under heavy pressure and the sleeve is forced upwardly there- 100 by, sliding upon the head 4 and being guided thereon as the bulb is expanded by air forced into it through the stem 14.

A supply of air under pressure is provided 105 at most filling stations for the use of motorists in inflating tires and the heavier and more expensive motor vehicles are commonly provided with an air pump. By carrying a jack of the construction herein described, 110 the motorist may very quickly and conveniently jack up his car by simply placing

the present device in position beneath the axle, attaching an air hose to the connection 16, and turning on the air, when he is at a station where a supply of air, under pressure, is provided, or when his car is equipped with an air pump. If an air supply or power driven pump are not available, then he may attach the ordinary air pump to the connection and in that way readily raise 10 the axle to the desired height.

A device of very simple construction is provided and one which may be manufactured at a minimum cost and as there are only three movable parts and no notched 15 members, dogs, ratchets, or gears are necessary, the liability of the device to get out of order is minimized, and its operation greatly facilitated.

Obviously, the particular construction and 20 configuration of parts may be varied within the scope of the appended claims, and I do not therefore limit myself to the particular form or arrangement shown.

Having thus fully described my invention, 25 what I claim is:—

1. A lifting device of the character described comprising a base member, a lifting member movable upon said base member, said members together forming a casing, and 30 an inflatable member within said casing.

2. A lifting device of the character described comprising a base member formed with a concavity, a lifting member slideable upon said base member and co-operating therewith to form a closer chamber, and an 35 inflatable member within said chamber seated within said concavity.

3. A lifting device of the character described comprising a base member formed 40 with a concavity in its upper end, a lifting member sleeved upon the base member and slideable thereon, said lifting member having a closed end opposing said concavity and said base member and lifting member together forming a closed chamber, an inflatable member in said chamber, and means on 45 said inflatable member for admitting fluid under pressure thereto, said base member being formed with an opening to receive 50 said means.

4. A lifting jack comprising a base mem-

ber having a head formed with a concavity in its upper end and a side wall of cylindrical form, a sleeve member fitting said head to slide thereon and having a closed upper end opposing said concavity, said head and sleeve member together forming a closed chamber, an inflatable and expandable air tight member in said chamber seated in said concavity, and a stem on said 60 inflatable member for admitting fluid thereto, said base member being formed with an opening extending through said head into said concavity to receive said stem.

5. A lifting jack comprising a base member 65 having a base flange to support the member in upright position and a cylindrical head formed with a semi-spherical concavity in its upper end, the outer surface of said head meeting said surface of said concavity 70 in a substantially sharp edge, a sleeve slideable upon said head and formed with a semi-spherical closed end opposing said concavity in the head, said head and sleeve forming a closed chamber, a rubber bulb in said chamber, and a stem on said bulb, said head being formed with an opening extending therethrough to receive said stem.

6. A lifting device of the character described comprising a casing expandable in 80 one direction only, an expandable fluid container within said casing and confined thereby to expansion in one direction only, and a lifting member operated by the expansion of said fluid container within said casing. 85

7. In a lifting device of the character described, the combination of an expandable fluid container, means for admitting fluid under pressure thereto, a base member, a hollow member slideable upon said base, said 90 base and hollow member together forming a tight expandable casing to completely enclose the expandable fluid container, and a lifting member upon said slideable hollow member.

In testimony whereof I affix my signature 95 in presence of two witnesses.

WILLIAM A. GIBSON.
